OTHER PUBLICATIONS

In the U.S. Patent and Trademark Office U.S. Appl. No. 13/485,894
Non-Final Office Action dated May 9, 2013, 8 pages.

Primary Examiner — Angela J Lee(74) *Attorney, Agent, or Firm* — Patton Boggs LLP(57) **CLAIM**

The ornamental design for a tablet holder, as shown and described.

DESCRIPTION

This application claims priority to U.S. patent application No. 13/485,894 filed on May 31, 2012.

FIG. 1 is a front view of a tablet holder (the front, left, right, and rear views are mirror images);

FIG. 2 is a top view of the tablet holder of FIG. 1;

FIG. 3 is a bottom view of the tablet holder of FIG. 1; and,

FIG. 4 is a front perspective view of the tablet holder of FIG. 1.
